UNITED STATES PATENT OFFICE

2,586,933

SHOE BOTTOM FILLING MACHINE

Leslie Garratt, Leicester, and Percy White, Worcester Park, England, assignors to United Shoe Machinery Corporation, Flemington, N. J., a corporation of New Jersey

Application January 3, 1951, Serial No. 204,112
In Great Britain January 28, 1950

7 Claims. (Cl. 12—79.6)

1

This invention relates to machines for filling the cavities in shoe bottoms, and more particularly to improvements in shoe bottom filling machines of the type disclosed in the United States Letters Patents No. 2,465,417, granted March 29, 1949 in the names of C. M. Bagshaw, F. C. Choice and J. W. Pratt and No. 2,465,501, granted, as of the same date, in the name of P. White.

In the use of machines of the type herein considered, bottom filling material such as a mixture of ground cork and a binder is placed in the cavity which customarily exists in accordance with general shoemaking practice, in the central portion of the forepart of a shoe bottom after a marginal portion of the upper materials has been lasted over an insole or like shoe-bottom member and prior to the application of an outsole to the shoe-bottom. In the case of a shoe of the McKay type the cavity is bounded by the overlasted marginal portion of the upper materials and, in the case of a shoe of welted construction, the cavity is bounded by the upstanding lip or rib on the insole to which the overlasted margin of the upper is secured.

The machine disclosed in each of the patents referred to comprises a matrix device including a flexible diaphragm which is arranged to bridge the cavity in the bottom of a shoe held thereagainst so that the diaphragm engages the portions of the shoe bounding the cavity. Each machine also includes means for clamping the shoe firmly against the diaphragm which may thereby become distorted so that marginal portions thereof follow the contours of the shoe bottom and generally accommodate themselves to irregularities in the height of the bounding wall of the cavity so as effectively to seal the latter along the sides and around the toe end of the shoe bottom.

The machine disclosed in each of said patents also has a reciprocatory device comprising a plunger and an associated pick-up sleeve arranged, at times, to overhang the operative end of the plunger which is arranged to move through a mass of filling material (conditioned by the application of heat and by agitation of the material in an agitating drum therefor) and to separate a quantity of the conditioned (i. e. fluent) bottom filling material from the mass thereof and to urge it through the matrix device and into the cavity.

In order that a complete cycle of operations of the machine may be accomplished in a short time and yet ensure that at least a latter portion of the bottom-filling operation may take place at

2

low speed to give the operator time to appreciate that the filling operation is completed and consequently to operate a by-pass valve to terminate the extrusion of material before an excess of material is delivered to the shoe bottom, the machines disclosed in the patents are provided with mechanical clutch devices (high speed and low speed) and operating mechanism therefor which were so organized that the machine cycle commenced at a relatively high speed but, at a predetermined time during the advancing movement of the plunger, the drive was transferred via a two-speed clutch device which continued the operation at a slower speed until, on the cavity being filled, the operator actuated the by-pass valve aforesaid, the drive then being transferred back to the high-speed clutch device and the cycle completed at high speed. The actuation of the by-pass valve at the end of the cavity-filling operation also resulted in the unclamping of the shoe.

While machines constructed as disclosed in the patents referred to above have proved capable of giving very good results, the means for cutting off the supply of filler material to each shoe and the somewhat complicated mechanical clutch devices and associated mechanism have not always proved as fully efficient as is desirable. The two-speed clutch devices, when operating satisfactorily demonstrated that, without doubt, the ability of the machine to run at two speeds during the cycle of operations resulted in a general saving of time but, in spite of this fact, the mechanical weaknesses of the clutch mechanism have not proved themselves easy to eradicate nor has any suitable and more reliable form of mechanical arrangement suggested itself.

The object of the present invention is to provide an improved shoe bottom filling machine which is reliable and conducive to efficient control on the part of an operator and is not as complex in construction as machines heretofore conceived for carrying out equivalent operations.

To this end and in accordance with an important feature of the invention, a matrix box or diaphragm is provided for forming a seal with the bottom of a shoe, the box or diaphragm being in combination with a two way or cut-off and by-pass valve which is reliably effective for its cut-off action in a plane approximately that of the matrix regardless of any variation in the consistency or fluidity of the particular bottom filling composition employed.

One other feature is the matrix box or diaphragm mounted in an inclined position for improved observation by an operator.

3

Another feature of the invention is a fluid pressure operated means or system for effecting the extrusion or bottom filling operation.

An additional feature is a multiple-speed fluid pressure operated drive in combination with automatic means for changing the speed together with a manual control for timing the operation of the automatic means.

These and other features of the invention including various novel details of construction and combinations of parts will be described as embodied in two forms of the machine illustrated and as pointed out in the appended claims.

In each of the machines illustrated a matrix device is employed that is similar in some respects to those disclosed in the patents referred to and also shoe clamping means for clamping a shoe with portions of the shoe bottom surrounding the sides and toe end of the cavity firmly in engagement with a diaphragm of the matrix device so that the cavity is bridged by the diaphragm, means comprising a reciprocatory plunger and an associated pick-up sleeve for introducing filling material between the diaphragm bridging the cavity and the shoe bottom to fill the cavity, and mechanical as well as fluid-pressure operated means for operating the shoe clamping means and the means for introducing the filling material into the cavity together with means for coordinating the action of various of the operating instrumentalities of the machine through appropriate operation of valve devices associated with said fluid-pressure operated means.

In the illustrative machines hereinafter described the fluid-pressure operated means comprises two pumps, viz. a high capacity pump and a low capacity pump. The high capacity pump is arranged to deliver oil, when permitted to do so, at a rate of some 13½ gallons per minute to a hydraulic circuit associated with a piston and cylinder device for operating the reciprocating plunger and its pick-up sleeve and with piston and cylinder devices for operating shoe clamping means and a cut-off valve associated with the matrix device. The low capacity pump is arranged to deliver oil to the hydraulic circuit at a rate of some 1½ gallons per minute. The fluid-pressure operated means also comprises valve gear for controlling the flow of oil in the hydraulic circuit. An operator-controlled treadle device is provided in the illustrative machines hereinafter described for actuating the valve gear to effect clamping of a shoe in operative position, for initiating a cavity-filling operation and for eventually terminating that operation and causing unclamping of the shoe.

Forward movement of the plunger commences at high speed, both pumps supplying oil to the piston and cylinder device actuating the plunger, and a cam-actuated lever, actuated in time relation to the movement of the plunger, automatically cuts out the supply of oil from the high-capacity pump at a predetermined time during the forward stroke of the plunger so that the speed of movement thereof is materially reduced (to approximately one-tenth of its fast speed) to permit the cavity-filling operation to be terminated at low speed for the purpose above referred to.

When the operator wishes to terminate the cavity-filling operation he will release the treadle device whereupon the shoe clamping means is caused to release the shoe, the cut-off valve automatically sealing the extrusion duct through

4

the matrix device at a locality substantially level with the diaphragm, and the high-capacity pump is reconnected with the portion of the hydraulic circuit feeding the piston and cylinder device actuating the plunger to cause the latter to complete its forward stroke, and to return to its fully withdrawn position, at high speed, a reversing valve automatically changing over the direction of movement of the plunger at the appropriate times. Surplus filling material picked up by the plunger and pick-up sleeve is returned to the agitating drum.

It will thus be appreciated that the two-speed movement of the plunger and pick-up device is effected without the employment of complicated mechanical clutch devices, and, from the following description, it will be seen that this movement and the coordination and timing of the operation of the shoe clamping means and the cavity-filling means is effected by fluid pressure operated means controlled by valve control gear of a relatively simple character.

In the accompanying drawings,

Fig. 1 is a front elevation of a machine embodying the present invention;

Fig. 19 is a detail plan view of parts associated with the valve shown in Figs. 17 and 18;

Fig. 20 is a detail view of the valve and parts associated therewith as viewed from below; and

Fig. 21 is a right-hand side elevation of a treadle actuated arrangement and associated

75

parts with which the modified form of the machine is provided.

The machine illustrated in Figs. 1-13 inclusive comprises a base portion 1 and a head casting 3 carried thereon. The base portion consists of two side members 5 in the form of plate-like castings which are substantially rectangular in outline and have substantially rectangular portions removed from their midportions as is seen in Fig. 2. The side castings have reinforcing ribs cast integrally therewith. The side members 5 are connected together by means of three square-sectioned upper tie bars 7 (Figs. 5 and 6) and four lower tie bars 9 (Fig. 5) extending widthwise of the machine, these tie bars bridging between the side members at the top and bottom thereof and being spaced apart in a direction extending from front to rear of the machine.

The head casting 3 bridges between the upper ends of the side members 5 of the base portion of the main frame at the front of the machine. The head casting carries a drum 11 (Fig. 6) for conditioning bottom filling material prior to its application to shoe bottom cavities, the drum comprising stationary front and rear walls 13 and 15 respectively and a rotatable cylindrical wall 17 extending therebetween all substantially as described in above-mentioned Letters Patent No. 2,465,417 with reference to the drum 21 described therein. Within the drum is a baffle 16 (Figs. 6 and 7) which, though differing somewhat in actual construction from that referred to as the plate 31 in said Patent No. 2,465,417, serves a similar purpose thereto. The baffle is secured to the stationary front and rear walls 13 and 15 of the drum. The rear wall 15 is secured to a rear upstanding portion 4 of the casting 3, the latter also having a hollow plate-like member 19 (Figs. 1 and 6) secured to the front thereof, this member extending across the machine and having a plate forming the front wall 13 of the drum secured to it. A door 20 is hingedly mounted on the member 19 and normally closes an opening therein providing access to the interior of the drum when required. The plate-like member 19 also carries a matrix device 21 (Fig. 4) which is somewhat similar to the matrix device 5 described in the prior Letters Patent No. 2,465,417, in that it has a flexible diaphragm 23 (Figs. 1, 3 and 4) which is arranged to engage marginal portions of a shoe bottom surrounding a cavity therein which is to be filled by the machine and means for supporting the diaphragm including a matrix box 25 and a plurality of fingers 27 therein which are spring pressed into supporting engagement with the back face of the diaphragm. The matrix device in the illustrative machine now being described is so mounted that the diaphragm 23, instead of being generally horizontal as in the machine disclosed in said Patent No. 2,465,417, occupies a position in which it extends downwardly and rearwardly in the machine (i. e. away from the operator) at an angle of some 35° to the horizontal. This arrangement of the matrix device enables the operator more readily to observe the heelward end of the shoe bottom cavity and so determine the instant at which the filling operation should be terminated. In presenting a shoe to the machine the operator will hold the shoe, bottom upwards but with the toe end pointing downwardly and away from him, in position against the diaphragm 23 while shoe clamping means is brought into operation as hereinafter described to clamp the shoe in position against the diaphragm with sufficient pressure to ensure

that the diaphragm is distorted by engagement of the marginal portion of the shoe bottom therewith, against the action of the spring-pressed supporting fingers 27, in such manner that the diaphragm bridges the cavity and effectively seals the cavity along the side walls thereof in preparation for the cavity filling operation.

For introducing filling material into the cavity between the diaphragm and the shoe bottom the illustrative machine is provided with a movable device comprising a reciprocatory plunger 29 (Fig. 6) and a pick-up sleeve 31 associated therewith which plunger and sleeve correspond to the plunger 19 and sleeve 15 described in said Letters Patent No. 2,465,417. The plunger 29 and pick-up sleeve 31 operate substantially in the manner described in said Patent No. 2,465,417, to pick up a quantity of filling material from a mass thereof in the agitating drum 11 and then to extrude the filling material so picked up into a cylinder 33 in a casting 35 (Figs. 3 and 6) to which the matrix device is secured and which itself is secured to the plate-like member 19 forming the front wall of the head casting. From the cylinder 33 the material is extruded into the cavity in the shoe bottom through a duct 37 (Fig. 3) extending through the matrix device, the duct having a cut-off valve 39 associated therewith. The valve 39 is somewhat similar to the valve referred to as the valve rod 160 in the prior Letters Patent No. 2,465,501 to White in that it comprises a plunger mounted for movement in a direction at least substantially perpendicular to the general plane of the matrix 23. The cut-off valve 39 in the illustrative machine now being described is arranged, prior to the clamping of a shoe in operative position in the machine, to be seated on a valve seating substantially in the plane of the matrix 23 so as to close the duct through the matrix device.

On the clamping of a shoe in the machine the valve is raised automatically to open the duct to the cavity so that filling material may be extruded into the cavity from the cylinder 33 as a forward end portion of the reciprocatory plunger 29 enters and moves along the cylinder.

The illustrative machine is provided with a treadle 43 (Figs. 1 and 2) which the operator may actuate (a) to effect clamping of the shoe; and to initiate the bottom-filling extruding action of the machine; and (b) to terminate the cavity-filling operation and to release the shoe when he observes that the cavity has been sufficiently filled. Actuation of the treadle to release the shoe automatically causes the valve 39 (Fig. 3) to be reseated on the valve seating above referred to so that the duct 37 through the matrix device is closed before the shoe is fully unclamped. The valve 39 is so constructed as arranged that, at the termination of the cavity-filling operation, it occupies such a position (see Fig. 3) that surplus filling material is diverted back to the drum 11 via a passage 44 in the valve stem and a duct 45 on the casting 35 as the reciprocatory plunger 29 completes its forward or "working" stroke. When the valve is raised during the filling operation the passage 44 does not communicate with the cylinder 33.

In the illustrative machine use is made of fluid-pressure operated means for actuating the shoe-clamping means and the reciprocatory plunger and pick-up sleeve device. In order that at least a final portion of the actual bottom-filling extrusion operation may take place at a relatively slow speed (so that the operator may

more readily be able to terminate the filling operation at the correct instant) while other portions of the machine cycle are effected at a relatively high speed (so as to minimize the time taken for a complete cycle of operations) the fluid-pressure operated means comprises two pumps—a high capacity pump 51 (Figs. 5 and 7) and a low-capacity pump 53—which at times are working in conjunction but, during a portion, at least, of the actual extrusion operation, the low-capacity pump alone is effective in operating the plunger 29.

The pumps 51 and 53 are both mounted in a box-like casting 55 (Figs. 5 and 7) and are of the rotary type, being driven continuously from an electric motor 57 secured in the base portion of the machine frame. The casting 55 is bolted to two of the lower tie bars 9 above a base plate 59 which also carries the motor 57.

The motor 57 has a double driving pulley 60 which, by means of belts 61, drives a pulley 63 secured on an end portion of a shaft 65 (Fig. 7) which projects outwardly from the casting 55, in bearings in which the shaft is journaled. The shaft 65 is directly coupled to the high capacity pump shaft by means of an Oldham coupling 67. The low capacity pump 53 is driven from the high capacity pump shaft through reduction gearing 69, 71 (Fig. 7).

The shaft 65 also has thereon a worm gear 73 engaging a worm wheel 75 secured on a shaft 77 journaled in bearings in the casting 55. A portion of the shaft 77 extends outwardly through the casting and has secured thereon a sprocket wheel 79 (Fig. 5) which, through a chain 81 (Figs. 5 and 7), drives a sprocket wheel 83 (Figs. 6 and 7). The sprocket wheel 83, in turn, rotates the drum 11 through a friction clutch 85 (Fig. 6), the drive to the drum (and the method of supporting the drum) being substantially as described in said Patent No. 2,465,417, with reference to the drum 21 described therein. The tension in the chain 81 is determined by a spring 82 (Fig. 7) connected to a bell-crank lever 84 carrying an idler sprocket wheel 86.

In the pump casting 55 is provided an oil reservoir 91 (Fig. 5) oil being admitted to the reservoir by means of a filler opening normally closed by a filler cap 95. A filter unit 97 (Fig. 5) is detachably secured to the rear of the casting 55 and exhaust oil from the hydraulic system is returned to the reservoir 91 through the filter unit. Oil from the reservoir is admitted to the pumps through appropriate intakes (not shown) and oil is fed by the high capacity pump 51 into the hydraulic circuit (hereinafter described) via an outlet pipe 99 (Figs. 5 and 7) while the low capacity pump 53 feeds the hydraulic circuit via an outlet pipe 101.

The shoe-clamping means is operated by fluid-pressure operated means and will now be described. Extending between the side members 5 are two horizontal and transverse rods 111, 113 (Figs. 2 and 3) which extend through transverse bores in a rear portion of a box-like casting 115 (see also Figs. 1 and 4) so as to support the latter. The casting 115 serves to house switchgear hereinafter described and also carries a transversely extending horizontal rod 117 on end portions of which two members 119 are carried. The members 119 have threaded into them (Figs. 3 and 4) lower end portions of tie rods 121 (one at either side of the machine) which extend upwardly and rearwardly and

have upper end portions secured by bolts 124 to arms 123 extending outwardly from the casting 35 (Fig. 3) supporting the matrix box 25.

Supported by the tie rods 121 is a casting 125 which extends between the tie rods and is located lengthwise thereof by means of collars 126 and locking collars 128 threaded on to lower portions of the tie rods. The casting 125 is secured in position upon the tie rods by means of clamping bolts 130 (Fig. 4).

The casting 125 has centrally formed therein a cylinder 127 the axis of which lies parallel to the axes of the tie rods 121. Within the cylinder are two opposed pistons 129 and 131. The piston 129 has a piston rod 133 secured therein and a light spring 135 surrounds the piston rod and is received between the piston 129 and the upper end wall of the cylinder 127. The piston rod is restrained against rotation by means of a stud 137 threaded through the upper end wall of the cylinder and received within a longitudinal guideway 139 in the piston rod 133. Secured to an upper end portion of the piston rod 133 is a block 141 having ribs 145 projecting laterally therefrom. The ribs are received within guideways in a member 143 on which is carried a shoe supporting rubber pad 147. The pad 147 is shaped to receive the vamp portion of a shoe on a last and is arranged to thrust the shoe upwardly so that marginal portions of the shoe bottom surrounding the cavity to be filled are thrust firmly into engagement with the diaphragm 23. The member 143 carrying the pad 147 is adjustable, lengthwise of the shoe, on the ribs 145, on the block 141. The member 143 is clamped in adjusted position on the block by means of a clamping screw 149.

The piston 131 has a downwardly extending piston rod 151 secured therein, the piston rod 151 extending through a lower end wall of the cylinder 127 provided by a plate 153. A spring 155, somewhat stronger than the spring 135, surrounds the piston rod 151 between the piston 131 and the plate 153 and normally urges the piston upwardly until a bifurcated head portion 157 on the piston rod 151 engages the plate 153. The head portion 157 is pivotally connected to a transversely extending lever 159 between the ends thereof. As seen from the front of the machine (Fig. 4) the right-hand end of the lever 159 is pivoted to a bracket 161 secured to, and depending from, the casting 125. The left-hand end of the lever 159 is pivotally connected to a lower end of a connecting rod 163 which extends upwardly and rearwardly, parallel to the axes of the tie rods 121, and at its upper end is pivoted to a transversely extending valve operating lever 167.

The lever 167 is pivotally mounted, midway between its ends, on a pin 169 carried by the casting 35 supporting the matrix box 25. The lever is received within an aperture in the casting and has a bifurcated right-hand end portion (as seen from the front of the machine) the limbs of which are received within recesses cut in a stem portion of the valve 39. The arrangement is such that, when the piston 131 is held in its uppermost position in the cylinder 127 by means of the spring 155 the valve 39 is held against its seating to close the duct 37 through the matrix box. When, however, the piston 131 is thrust downwardly against the action of the spring 155, as will be hereinafter described, the valve 39 is raised to open the duct through the matrix box in preparation for a cavity filling operation.

For operating the pistons 129 and 131 oil is admitted to a central portion of the cylinder

127 through a port 171 in the cylinder wall, the port 171 communicating with a pipe 173 leading from a shoe clamping control valve 175 (Fig. 3). The valve 175 is arranged, prior to the initiation of a cycle of operations by actuation of the treadle 43, to connect the pipe 173 with exhaust so that the springs 135 and 155 (Fig. 4) lower and raise the pistons 129 and 131 respectively. On actuation of the treadle 43 the valve 175 is arranged to disconnect the pipe 173 from exhaust and to connect it with an oil supply line as hereinafter described so that oil is admitted to the cylinder 127 via the port 171. At first the piston 129 is moved upwardly against the action of the spring 135 until upward movement of the pad 147 is resisted by engagement with the shoe. Then, as the pressure builds up in the cylinder 127, the pad thrusts the shoe bottom more firmly against the diaphragm and the piston 131 moves downwardly against the action of the stronger spring 155 to raise the cut-off valve 39.

Ports 177 and 179 (Fig. 3) are provided at upper and lower ends of the cylinder 127 and communicate with a pipe 180 (Fig. 4) the purpose of which is to drain away any oil seeping past the pistons 129 and 131. For actuating the plunger 29 for effecting the extrusion of the filling material into the shoe bottom cavity the following arrangement is provided.

A horizontally disposed cylinder 181 (Figs. 5, 6 and 8) provided with end caps 183 is secured to the undersides of two of the upper tie bars 7 of the base portion of the machine frame. A piston 185 operates within the cylinder and has a piston rod 187 extending rearwardly therefrom through a packing gland 189 in the end cap 183 at the rear of the cylinder 181. A rear end portion of the piston rod 187 is secured to a cross head 191 which is guided for forward and rearward movement by guide bars 193 secured, at their forward ends, to the rear one of the end caps 183 and, at their rearward ends, to the rear-most tie bar 7.

The cross head 191 is connected by a link 194 (Figs. 5 and 11) to a lower arm 195 of a lever secured, mid way between its ends, to a cross shaft 197 (Fig. 5) (see also Figs. 11 and 12) journaled in bearings in brackets 199, 200 and 202 (Fig. 12) secured to the side members 5 of the machine-frame or to two of the tie bars 7 (in the case of the bracket 200). The lever just referred to has an upper arm 201 (Fig. 6), an upper end portion of which is connected, via a link 203, to a crosshead 205 on the rearward end of the plunger 29. The crosshead 205 (Fig. 6) is guided for reciprocating movements forwardly and rearwardly of the machine by means of two parallel guide rods 207 (Fig. 12) secured, at forward ends thereof, to the head casting 3 and, at rearward ends thereof, in bores in the bracket 200.

The plunger 29 extends forwardly through a bearing bore in a sleeve member 211 (Fig. 6) secured in a rear wall of a rearward box-like extension 213 of the head casting 3. The pick up sleeve 31 is slidably mounted on a forward end portion of the plunger and a coil spring 215 received within an enlarged rear portion of the bore through the pick up sleeve (and held therein by means of a plug in the rear end of the bore) grips the plunger and ensures that the pick up sleeve moves with the plunger unless movement of the sleeve is arrested whereupon the plunger may move relatively to the sleeve. The sleeve 31 extends through the rear wall 15 of the drum 11 and into the box-like extension 213 of the head casting. The rearward end of the sleeve,

during the return (i. e. rearward) stroke of the plunger 29, engages an adjustable stop (described hereinafter) which arrests rearward movement of the sleeve while the plunger completes its rearward movement. At the completion of this movement the sleeve overhangs the front end of the plunger and the amount by which the sleeve so overhangs the end of the plunger is determined by the setting of the adjustable stop just above referred to.

When it is desired to use the machine to fill cavities in the larger sizes of shoes the stop will be adjusted so that it arrests movement of the sleeve earlier in the return stroke of the plunger so that, at the conclusion of the return stroke of the plunger, the sleeve overhangs the forward end of the plunger a considerable amount. This ensures that, on the next forward stroke of the plunger and sleeve, a relatively large amount of filling material will be picked up by the sleeve. When it is desired to use the machine to operate on small shoes the stop will be set further rearwards in the machine so that movement of the sleeve is not arrested until a later time during the return stroke of the plunger thus resulting in a smaller overhang of the sleeve. Under these circumstances, during the next forward stroke of the plunger and sleeve, the amount of filling material picked up by the sleeve will be smaller than in the previous case. Forward movement of the sleeve is arrested by engagement of the front end of the sleeve with the rear end of portions of the casting 35 providing the cylinder 33 and, on further forward movement of the plunger, material picked up by the sleeve is extruded into the cylinder 33 and thence through the matrix box as described in the Patent No. 2,465,417, above referred to. By suitable adjustment of the stop the operator may ensure that the change over to slow speed of the extruding device occurs just before the cavity filling operation is ready for termination whatever be the size of the shoe being operated upon.

The adjustable stop for determining the amount by which the pick up sleeve overhangs the front end of the plunger 29 is provided by a bifurcated upper end portion of an arm 221 (Fig. 6) (see also Fig. 7) which is secured to (and projects upwardly from) a cross shaft 223 journaled in bearings in the extension 213 of the head casting 3. The bifurcated portion of the arm 221 embraces the plunger 29 at a locality to the rear of the pick up sleeve. The shaft 223 has secured thereon a worm wheel 225 (Fig. 7) engaged by a worm gear 227 secured to a shaft 229 extending forwardly (Fig. 6), through bearings in the head casting 3, to the front of the machine where it is provided with a hand knob 231 by which the shaft 229 may readily be rotated by the operator to adjust the stop formed by the arm 221 forwardly or rearwardly in the machine.

The end caps 183 of the cylinder 181 are provided with ports 233, 234 (Fig. 8) communicating with the opposite ends of the cylinder and flow of oil to and from the cylinder is controlled by a reversing valve 235 (Figs. 7 and 10) and by a speed control valve 237 (Figs. 5, 7 and 9).

The hydraulic circuit will now be described.

Oil from the low capacity pump 53 (Figs. 5, 7 and 13) is fed via the pipe 101 to a junction 243 (Fig. 5) which communicates, via a pipe 245, with a pressure gauge 247 (see also Fig. 13) for indicating the pressure of oil supplied by the low capacity pump. The junction 243 also communicates, via a pipe 249, with a second junction

250 (Fig. 13), which communicates (i) via a pipe 253 with a pressure relief valve 255 for determining the maximum pressure of oil fed into the hydraulic circuit by the low capacity pump, and (ii) via a pipe 257 (see also Fig. 5) with a third junction 259. Exhaust oil from the relief valve 255 is returned via a junction 268 and pipe 269 to the reservoir. The junction 259 communicates, via a pipe 261, with another pressure relief valve 263 (for a purpose hereinafter described) and, via a pipe 265 with another junction 270 communicating, via a pipe 272 with an inlet port 267 of the shoe clamping control valve 175, the junction 270 also communicating with a pipe 379 leading from the speed control valve 237. The valve 255 is set to blow off at a pressure of about 120 lbs. per sq. in., while the valve 263 is set to blow at about 100 lbs. per sq. in.

The shoe clamping control valve 175 (Fig. 9) comprises a casing 271 provided with end caps 273 with longitudinal bores in which slides a valve stem 275 having lands 277, 279 and 281 (see also Fig. 13) thereon. The valve 175 also has an exhaust port 285, communicating, via a pipe 287 (Figs. 5, 9 and 13) with the oil reservoir (through the filter unit) and a port 289 communicating, via the pipe 173, with the port 171 of the shoe clamping cylinder 121.

A spring 291 (Figs. 9 and 13) received within the valve casing 271, between the forward one of the end caps 273 and the land 271, urges the valve stem 275 rearwardly into a position (as shown in Fig. 9) in which the port 289 communicates with the exhaust port 285, the lands 279, 281 preventing oil from flowing through the inlet port 267. The springs 135 and 155 then hold the pistons 129 and 131 respectively in their lowered and raised positions, i. e. with the cut-off valve 39 closed and the shoe clamping roll 141 lowered.

When it is desired to clamp a shoe in the machine the operator will depress the treadle 43 which, through mechanism hereinafter described, moves the valve stem 275 (Fig. 9) forwardly, against the action of the spring 291, into a position in which the land 279 blocks off communication between the ports 289 and 285 and communication is established between the ports 267 and 289 so that oil is supplied to the inlet port 171 of the cylinder 121 and shoe clamping and opening of the cut-off valve are effected as above referred to.

Oil from the reducing valve 263 flows into a pipe line 305 (see Figs. 5, 7 and 13) communicating with an inlet port 307 of the reversing valve 235 (Figs. 10 and 13). The valve 235 comprises a casing 309 provided with end caps 311 in which is slidably mounted a valve stem 313 having thereon lands 315, 317, 319 and 321. The valve 235 also has ports 323 and 325 communicating, via pipe lines 327 and 329, with the ports 233 and 234 respectively at the front and rear ends of the cylinder 181. The reversing valve 235 also has two exhaust ports 335 and 337 both communicating with a pipe 339 leading back, via the filter unit 91, to the oil reservoir.

Prior to the commencement of a cycle of operations of the machine the reversing valve stem 313 is held, by means hereinafter described, in a position (shown in Fig. 10) in which communication is established between the port 234 of the cylinder 181 and the inlet port 307 of the reversing valve and between the port 233 of the cylinder 181 and the exhaust port 335 of the reversing valve.

Oil, under pressure from the low capacity pump

above described, then holds the piston 185 (to the left as viewed in Figs. 5 or 8) in its most forward position with the plunger 29 fully retracted (to the right as seen in Fig. 6) ready to commence a forward extrusion stroke.

Oil from the high capacity pump 51 flows via the pipe 99 to a junction 343 (Figs. 5 and 13) connected (i) by a pipe 345 (Fig. 13) to a pressure relief valve 347 which determines the pressure of oil fed into the hydraulic circuit by the high capacity pump and is set to open at about 120 lbs. per sq. inch, (ii) by a pipe 349 to a pressure gauge 351 indicating the pressure of oil supplied to the high capacity pump, and (iii) by a pipe 353 to an inlet port 355 of the speed control valve 237. Exhaust oil from the pressure relief valve 347 flows via a pipe 357 (Fig. 13) and through the junction 268 and the pipe 269 back to the reservoir in the casting 55.

The valve 237 (Fig. 9) comprises a casing in which there is a valve stem 363 having four lands 365, 367, 369 and 371 thereon and the stem 363 extends through caps 373 at both ends of the casing of the valve. The valve 237 has in addition to its inlet port 355 two outlet ports 375 and 377, the former communicating with the pipe 379 (Figs. 5 and 13) above referred to. The port 377 of the valve 237 communicates with a pipe 383 (Figs. 5, 7, and 13) leading back to the reservoir via the filter unit. Prior to the initiation of a cycle of operations of the machine the valve stem 363 occupies such a position that the port 355 communicates with the port 377 (as shown in Fig. 9) and oil from the high capacity pump merely circulates idly back to the reservoir.

The pipe 379 communicates, as above described, via the junction 270 with (a) the pipe 272 leading to the shoe-clamping valve and (b) with the pipe 265 and hence, via valve 263, with the pipe line 305, and, when during a cycle of operations of the machine, the valve stem 363 of the speed control valve is moved forwardly (by means hereinafter described) such a distance that the inlet port 355 communicates with the port 375 (and the land 369 blocks communication between the ports 355 and 377) oil delivered from the high capacity pump is supplied by the circuit above described to the pipe line 305 and, thence with oil from the low capacity pump, flows, via the reversing valve, to the cylinder 181 to move the piston 185 at high speed.

The rates of flow from the two pumps are approximately 13½ gallons per minute and 1½ gallons per minute respectively. Thus when the speed control valve is so conditioned that oil from the high capacity pump is delivered to the pipe line 305 a total delivery of 45 gallons per minute is obtained thus giving a speed of movement of the piston 185 ten times as great as when the cylinder 181 is supplied with the oil only by the low capacity pump.

The means for actuating the various control valves will now be described.

The treadle 43 is secured on a cross shaft 395 (Fig. 1) carried between the side members 5 of the machine frame, to which shaft depending levers 401, 402 are also secured. The treadle 43 is normally urged upwardly by means of a spring 403 (Figs. 1 and 5) connected between the lever 401 and the frame. The treadle has a rearwardly extending arm 405 (Fig. 5) coupled, by an upwardly extending link 407, with a rearwardly extending arm 409 (Figs. 3 and 5) of a bell crank lever also having an upwardly extend-

ing arm 411. The bell crank lever 409, 411 is

pivoted on a stud 413 extending transversely of the machine and carried by a lug on the casting 115. The arm 411 is bifurcated at its upper end and embraces a portion of the stem 275 of the shoe clamping control valve 175 which portion extends through the forward one of the end caps 273 of the valve casing 271.

Pins 415 extend inwardly from the bifurcated portion of the arm 371 into an annular space between flanges 417 in the valve stem 275. The arrangement is such that, on depression of the treadle 43, the link 407 is raised to swing the bell crank lever 409, 411 anticlockwise (as seen in Fig. 5) to a limit determined by engagement of the arm 411 with a stop screw 419 secured in the casting 115, such movement being effective to move the valve stem 275 forwardly to the position above referred to in which oil is admitted to the cylinder 121 to effect clamping of a shoe presented to the machine against the diaphragm and opening of the cut-off valve 39.

Depression of the treadle 43 also causes the depending levers 401, 402 (Fig. 1) to rock (anticlockwise as seen in Fig. 5) with the cross shaft 395 thereby moving links 421, 422 connected to the arms 401, 402 respectively rearwardly in the machine.

The link 421 is connected, at the rearward end thereof, to a depending arm 423 of a two-armed lever also having an upwardly extending arm 425. The lever 423, 425 (Fig. 5) is pivotally mounted, near the right-hand side of the machine (as seen from the front), on a cross shaft 427 supported by the side members 5 of the machine frame. The arm 425 is connected at its upper end by a link 429 to the knuckle of a toggle comprising links 428, 430 (Fig. 11). The link 428 is pivoted on a stud 432 carried by the machine frame, and the upper end of the link 430 is coupled to a rearwardly extending arm 431 (see also Fig. 12) of a two-armed lever 431, 433 freely pivoted on a cross shaft 45 extending between the side members 5 of the machine frame. The arm 433 of the two-armed lever just referred to is bifurcated and extends upwardly in the machine (see also Figs. 12 and 13). Between the limbs of the arm 433 (at the upper end thereof) extends a pivot pin 437 on which is freely pivoted a two-armed lever having a downwardly extending arm 439 normally lying between the limbs of the arm 433 and substantially in alignment therewith) and an arm 441 extending upwardly and rearwardly in the machine. Anticlockwise rotation (as seen from the right-hand side of the machine) of the two-armed lever 439, 441 relatively to the bifurcated arm 433 is limited by a stop screw 443 (Fig. 11) (carried by a small plate extending between rearward edge faces of the limbs of the arm 433) engaging a stop face on the rearward edge face of the arm 439. The lower end of the arm 439 has a threaded bore extending therethrough in which bore is received a stop screw 445 which extends forwardly through the arm and is secured in adjusted position therein by means of a lock nut. The screw 445 engages a rear face of a flange 446 on a portion of the valve stem 363 which extends rearwardly through the rear end cap 373 of the speed control valve 231.

When the lever 423, 425 (Fig. 5) is swung anticlockwise on depression of the treadle 43 as above referred to the toggle formed by the links 428, 430 is straightened, to a position determined by engagement of a stop 434 (Figs. 5 and 11) (carried by a fixed portion of the machine) with the arm 425 and swings the lever 431, 433

(Figs. 11 and 13) anticlockwise thus carrying the lever 439, 441 (Fig. 13) forwardly in the machine and causing the screw 445 (Fig. 11) to move the valve stem 363 of the speed control valve forwardly to a position in which the inlet port 355 (Fig. 9) communicates with the outlet port 375 and the land 369 blocks off communication between the port 355 and the exhaust port 377. Oil from the high capacity pump is then delivered into the pipe line 305. Depression of the treadle is also effective (through means shortly to be described) to move the reversing valve stem 313 into a position in which the inlet port 307 communicates, through the port 323, pipe 327 and port 233 with the forward end of the cylinder 181 (Fig. 8).

Oil from the pipe line 305 (fed by both the high and low capacity pumps) is thus effective to move the piston 185 rearwardly at high speed and the plunger 29 is thus moved forwardly to carry the pick up sleeve 31 across the drum 11 to pick up filling material therefrom, this movement occurring at high speed.

When the two armed lever 431, 433 is swung anticlockwise (Figs. 11 and 13) to move, through the lever 439, 441, the valve stem 363 of the speed control valve as above described, a roll 447 (see Fig. 12) on a transverse pivot pin secured in the upper end of the arm 441 engages a peripheral surface of a cam 449 adjustably secured on a boss 451 secured to the cross shaft 197. The cam 449 because of its mounting on the shaft 197 is rotated in time relation with movement of the piston 185 and hence of the plunger 29.

The cam 449 is so adjusted relatively to the boss 451 that, when the plunger 29 has completed some three-quarters of its forward stroke, a rise 453 on the cam 449 (Fig. 11) engages the roll 447 and swings the lever 439, 441 clockwise (as seen in Fig. 11) about its pivotal connection with the arm 433 of the lever 431, 433. Such movement of the lever 439, 441 brings about a displacement of the valve stem 363 to the left, as seen in Figs. 5 and 11, of such an amount that the land 369 blocks off the inlet port 355 (Fig. 9) and terminates delivery of oil from the high capacity pump into the pipe line 305. At this time the oil from the high capacity pump is circulated back to the oil reservoir by the pressure reducing valve 347.

Movement of the plunger 39 is now effected only as a result of the action of the low capacity pump and it is during this time that at least the end portion of the extrusion of filling material into a shoe bottom cavity is arranged to be effected by appropriate adjustment of the stop provided by the arm 221 (Fig. 6) as aforesaid.

The purpose of the relief valve 263 (which is set to blow at some 100 lbs./sq. in. pressure as above referred to) is to ensure that, if at the time the oil supply from the high capacity pump is cut off from the pipe line 305, the pressure in the line 305 falls, the pressure in the circuit up to the valve 263 will not, at this time, fall below the pressure at which the valve 263 is set. This ensures that adequate pressure is maintained in that part of the circuit which supplies oil to the shoe clamping cylinder to ensure that the clamping device maintains the shoe firmly clamped against the diaphragm throughout the time when filling material is being extruded into the cavity in the shoe bottom.

When the operator desires to terminate the cavity filling operation he will remove his foot from the treadle 43 whereupon the spring 403

causes the lever 401 to be restored to its initial position thus breaking the toggle 428, 430 and swinging the levers 431, 433 and 439, 441 clockwise (Figs. 5 and 11) to carry the roll 447 away from the cam 449. At the same time the link 407 (Fig. 5) is moved downwardly to swing the lever 409, 411 clockwise to restore the stem 275 of the shoe clamping valve 175 to its initial position in which the port 171 of the cylinder 127 is connected to exhaust thus allowing the springs 155 and 135 (Fig. 4) to close the cut-off valve 39 and to unclamp the shoe, the spring 155 being assisted by a spring 156 connected between the lever 159 and a collar on the left-hand one of the rods 121.

In order to prevent the speed control valve stem 363 (Fig. 9) from being moved (by a spring 455 surrounding the valve stem between the land 365 and the forward end cap 373) away from its position in which supply of oil from the high capacity pump to the pipe line 305 is cut off, and thereby to prevent movement of the plunger at high speed, until the shoe is unclamped and the cut-off valve is fully closed the following arrangement is provided.

A forward portion of the valve stem 363 is provided with a notch 457 (Fig. 9) into which teeth of pawls 459 are urged by means of spring-pressed plungers 461 engaging fingers 463 on the pawls. The pawls are pivoted on transverse pins carried by the forward end cap 373 which is recessed to receive the pawls. The plungers 461 are received within horizontally extending bores in the end cap. The pawls engage the notch in the valve stem when the latter has been moved forwardly under the action of the cam rise 453 on the roll 447 (Fig. 11) to the position in which oil supply from the high capacity pump is blocked off from the supply pipe line 305. The pawls retain the valve stem 363 in this forward position (even though the levers 431, 433 and 439, 441 (Fig. 13) move to carry the screw 445 (Fig. 11) away from the rearward end of the valve stem 363 when the treadle 43 is released) until a cup-like member 465 (Fig. 9) secured to the rearward end of the valve stem 275 of the shoe clamping control valve 175 has moved rearwardly (to effect unclamping of the shoe and closing of the cut-off valve) sufficiently far for the member 465 to strike the fingers 463 of the pawls and to rock the latter out of engagement with the notch 457, it being understood that the valves 175 and 237 are mounted with their valve stems in axial alignment, the clamping control valve 175 being supported on tie bars 466 (Fig. 5) extending between the side members 5 and the speed control valve 237 being supported on a tray 470 (Figs. 5 and 7) carried on top of the casting 55.

On being released by the pawls 459 the stem 363 (Fig. 9) is moved rearwardly by the action of the spring 455 only so far as to effect communication between the ports 355 and 375 so that the plunger 29 completes its forward stroke, and at least the majority of its rearward stroke, at high speed, the position of the reversing valve being automatically changed at the termination of the forward stroke by means hereinafter described. For holding the valve stem 363 in the position just referred to at this time there is provided a bell crank lever 467, 469 (Figs. 5 and 11) pivotally mounted on a stud 472 carried by the right-hand one of the side members 5 (Fig. 7), the arm 467 being bifurcated at a lower end portion thereof (Fig. 12) the bifurcated portion embracing the rear end portion of the stem

363 and being received between the flange 447 (Fig. 11) and a second flange 471 thereon.

The other arm 469 of the bell crank lever has a roll 473 (Fig. 11) mounted thereon, the roll being engaged at times by the peripheral surface of a disc 475 (Fig. 13) secured to the cross shaft 197. The bell crank lever 467, 469 is rotated about its pivot as a result of movement of the valve stem 363 and the disc 475 is rotated with the cross shaft 197 on movement of the plunger 29.

Prior to the commencement of a cycle of operations of the machine the roll 473 is received within a depression 477 (Fig. 11) in the peripheral surface of the disc 475 (as is seen in Figs. 5 and 11), but when the treadle is depressed and the valve stem 363 is moved forwardly, the roll 473 is moved out of the depression 477 and, as the disc rotates, the roll 473 is engaged by the concentric portion of the periphery of the disc. When the stem 363 receives its additional forward movement, under the action of the cam rise 453 on the roll 447 on the lever 441, 439, the roll 473 is moved away from the periphery of the disc 475 and, when the valve stem 363 is released by the pawls 459, its movement towards the rear of the machine is arrested by the roll 473 again engaging the periphery of the disc 475. The valve stem 363 is held in this position until the plunger 29 has nearly completed its return stroke when the depression 477 comes opposite the roll 473 and the lever 467, 469 is allowed to swing anticlockwise, as seen in Figs. 5 and 11, as the valve stem 363 is moved to its most rearward position by the spring 455. This position is the initial position of the valve stem in which oil from the high capacity pump is circulated idly back to the reservoir. The final portion of the rearward stroke of the plunger 29 thus occurs under the action of the low capacity pump alone.

For controlling the reversing valve the following mechanism is provided. The link 422 (bottom of Figs. 5 and 7) is connected, at its rearward end, to a depending arm 476 of a bell crank lever freely pivoted on the cross shaft 427 near the left-hand side of the machine (as seen from the front thereof). This bell crank lever also has a rearwardly extending arm 478 (Fig. 5) connected by a pin-and-slot connection with a lower end portion of a substantially vertical bar 481 (Figs. 5, 11 and 12) an upper end portion 483 of which extends forwardly in the machine (Figs. 6 and 11) and is received between guide flanges 485 (Fig. 12) spaced apart axially of the shaft 197. The bar 481 is urged forwardly and downwardly by means of a spring 487 (Fig. 11) extending between the bar and a bracket 489.

A rearwardly extending arm 491 (Fig. 13) of a two-armed lever 491, 495 freely pivoted on the shaft 435 has a hardened block 493 (Fig. 11) thereon which is arranged to be received in a recess 497 in the bar 481. The arm 495 extends upwardly and has therein an adjustable stop screw 499 which is arranged to engage the rearward end of the valve stem 313 (Fig. 13) of the reversing valve 235.

Secured to the cam shaft 197 is a segment 503 having lugs 505 and 507 (Fig. 11) extending transversely thereof in opposite directions, one from each side face of the segment. The lug 505 has a rearwardly extending stop screw 509 extending therethrough, while the lug 507 has a forwardly extending stop screw 511 extending through it.

Prior to the commencement of a cycle of operations of the machine the parts just described occupy the positions shown in Figs. 5 and 11. The reversing valve stem 313, which is urged rearwardly by a spring 515 surrounding the stem between the front end cap of the valve and the land 315, at this time occupies a position determined by engagement of the arm 495 with the stop screw 511, the arm 495 being just clear of the stop screw 517 and the block 493 being held just above the bottom wall of the recess 497 in the bar 481 as seen in Fig. 11. In this position of the valve stem the rear end of the cylinder 181 is in communication with the oil supply and the plunger 29 is held in its most rearward position. During depression of the treadle 43 the bell crank lever 476, 478 (bottom of Fig. 5) is rocked anticlockwise and the bar 481 is raised so that the block 493 on the arm 491 is engaged by the lower wall of the recess 497 of the bar 481 and, as the bar continues its upward movement the lever 491, 495 is swung anticlockwise, on such upward movement of the bar 481 to move the reversing valve stem forwardly into a position in which the port 233 (Fig. 8) at the front end of the cylinder 181 is connected to the oil supply and the port 234 at the rear end of the cylinder is connected to exhaust. The piston 185 is thus moved rearwardly and, in so doing, rocks the shaft 197 (Figs. 5 and 11) and swings the segment 503 in an anticlockwise direction until, as the plunger reaches the forward limit of its stroke, the stop screw 509 engages the bar 481 and moves it rearwardly slightly to disengage the recess 497 from the block 493 on the arm 491. The lever 491, 495 is thus free to swing clockwise and the valve stem 313 of the reversing valve is moved rearwardly under the action of the spring 515 into a position in which the rearward port 234 of the cylinder 181 is connected to the oil supply and the forward port 233 is connected to exhaust. Movement of the lever 491, 495 in a clockwise direction (and hence movement of the reversing valve stem 313 rearwardly) at this time is limited by the arm 495 engaging a stop screw 517 (Fig. 11) in the bracket 489 which is supported on the rearmost tie bar 7.

The piston 185 is then moved forwards to carry the plunger 29 rearwardly during which movement the segment 503 is swung clockwise until, as the plunger 29 approaches the end of its backward stroke (and after the oil supply from the high capacity pump has been shut off from the pipe line 305 feeding the reversing valve as hereinbefore described) the stop screw 511 (Fig. 11) on the segment 503 engages the arm 495 and rocks the lever 491, 495 slightly anticlockwise but insufficiently to change over the reversing valve fully to its other position.

The treadle 43 will have been released by the operator, during the preceding forward stroke of the plunger 29, when he is satisfied that the shoe bottom cavity is sufficiently full and while at this time the plunger 29 will not have completed its forward stroke and the block 493 (Fig. 11) is still engaged by the bottom wall of the recess 497 in the bar 481, the bell crank lever 476, 478 (Fig. 5) and shaft 427 are able to swing clockwise, although the bar 481 is maintained in its raised position by means to be described below, because of the pin-and-slot connection between the lower end of the bar 481 and the arm 478 of the bell crank lever.

To maintain the bar 481 in its raised position 75

to ensure that the reversing valve cannot be moved over until the piston 185 has completed its forward stroke even though the treadle 43 is released by the operator, the upper end portion 483 (Fig. 11) of the bar 481 rests upon the peripheral surface of a boss 519 between the flanges 485 (Fig. 12), the boss having a flat 520 thereon which permits the bar 481 to be fully lowered only towards the end of the rearward stroke of

10 the plunger 29. When the bar 481 is lowered to its initial position as the plunger 29 completes its rearward stroke the recess 497 is lowered until the lower wall thereof can ride beneath the block 493, the bar 481 being then moved forwards by the spring 487 until the front wall of the recess 493 engages the rear face of the block 493.

For maintaining a supply of filling material in the drum 11 the illustrative machine is provided with a hopper 521 (Figs. 1, 2, 6 and 7) secured to a rear wall of the casting 3 and also supported by a large headed bolt 523 (Fig. 6). The hopper has inner and outer walls of sheet metal with a lining of asbestos therebetween. 20 The sides of the hopper are provided with additional sheet metal walls (not shown) spaced inwardly of the composite walls just referred to, the space between the additional walls and the composite walls providing steam jackets for the hopper. The hopper is also provided with a hinged cover 525. The lower end of the hopper opens into the drum 11 through an opening 527 (Figs. 6 and 7) extending through the front wall of the hopper and the rear wall 15 of the drum 30. 35 Steam may flow into the steam jackets in the hopper through openings in the front wall of the hopper and aligned openings in the rear wall of the casting 3 which openings communicate with a steam jacket in the portion 4 of the casting 3. The latter steam jacket communicates with a forwardly and rearwardly extending passage 530 (Fig. 6) in the head casting which passage also communicates, at the front of the machine, with a steam jacket in the plate-like member 19.

The steam jackets in the member 19 and the portion 4 of the head casting serve to maintain the drum and the cylinder 33 in a heated condition and this is further facilitated by the fact 50 that the baffle 16 is hollow and is heated by steam circulating therethrough from the steam jackets last referred to. To prevent undue loss of heat by radiation the drum is surrounded by a sheet metal cover 535 having an inner lining of asbestos.

The passage 530 communicates with a boiler 531 extending transversely of the machine in the head casting 3 (Fig. 7), and a damper 532 slideable forwardly and rearwardly in the passage 530 60 under the control of a rod 534 extending through the member 19 and having a knob 536 (Figs. 3 and 6) thereon, controls the relative rate of flow of steam to the jackets in the member 19 and in the portion 4 of the casting 3. The boiler has 65 therein an immersion heater 533 (Fig. 7) and is supplied with water through a feed device 535 from a water tank 537 (Figs. 6 and 12). The tank 537 has a filler opening normally closed by a vacuum cap 539 (Fig. 6), a rubber gasket of which is firmly thrust against the walls surrounding the filler opening by means of a toggle lever 541 to provide an air-tight joint. Water is fed from the tank by a pipe line 543 (Fig. 2) and stop cock 545, air being permitted to enter the tank via a pipe 547 whenever the level of water

in the feed device 535 falls below the level of the lower end of the pipe 547.

The tank 537 is carried by a frame 549 hinged by means of a forwardly and rearwardly extending rod 551 (Fig. 12) to the bracket 202 at the left-hand side of the machine. At the right-hand side of the machine the frame 549 is supported by two springs 553 surrounding pins 555 secured in the right-hand side member 5. The upthrust of the springs may be adjusted by means of collars 557 threaded on the pins 555. When the water level in the tank 537 falls below a certain amount the springs 553 lift the right-hand side of the frame 549 causing it to pivot slightly anti-clockwise (as seen in Fig. 12) and this pivotal movement is caused to actuate a microswitch 559 (the operating member of which is engaged by a stop screw 556 on a lug 558 on the frame 549) to operate a contactor 560 (Fig. 5) at the rear of the machine to switch off the supply of electric current to the boiler heater 531 and to operate a warning light 561 (Fig. 1) at the front of the machine, so as to warn the operator that the tank is in need of being refilled with water.

The hopper 521 has a thermostat (not shown) fitted therein which is arranged to cut down the supply of electric current to the heating element in the boiler when the material in the hopper is sufficiently hot.

The matrix device is provided with three electrically energized heating cartridges (held in place by screws 563, Fig. 3) for maintaining the matrix device at an appropriate temperature. Supply of electric current to these elements is also controlled by the contactor 560 (Fig. 5). A second contactor 569, also at the rear of the machine is provided for switching on or off the electric motor 57. Contactor 569 is controlled by a "start-stop" switch 571 on a panel 567 in the casting 115 at the front of the machine. The contactor 560 is controlled by a switch 565 on the panel 567 but it can, however, only be energized if the micro switch 559 is closed, i. e. if there is an adequate supply of water in the tank 537.

Should, at any time, it be desired to admit steam to the inside of the drum 11 to hasten the conditioning of the material therein there is provided a needle valve operated by a hand knob 575 (Fig. 1, 2 and 6) placed at the front of the machine and with its axis vertical, this valve controlling admittance of steam to the drum 11 from the steam jacket in the plate-like member 19 via an opening in the front wall 13 of the drum.

Furthermore should the operator wish to take a sample of the material in the drum 11 he may open a small trap door 581 (Fig. 1) in the main door 20 providing access to the drum and insert a spatula beneath a scraper 583 (Fig. 7) in the drum 11 which scraper acts to scrape off material from the revolving cylindrical wall of the drum after the material has been milled round between the baffle 16 and the wall 17 of the drum. The trap door 581 is swung aside about a pivot provided by a spindle projecting rearwardly from a small hand knob 585 for manipulating the trap door.

The procedure followed in filling the cavity in the bottom of a welt shoe with the aid of the illustrative machine will now be described. Assuming that the motor 57 is running and rotating the cylindrical wall 17 of the drum 11, the water tank is adequately supplied with water, the hopper is adequately supplied with filling material and that the various heating elements have been

switched on for a sufficient period of time to ensure that the filling material in the drum 11 has reached a smooth and fluent condition, and assuming that all necessary preparatory operations including that of trimming away unwanted portions of the insole lip and upper materials have been performed on the shoe, the operator will take the shoe and present it with its bottom against the diaphragm 23 (and with its toe end pointing away from him). While he holds the shoe thus positioned against the diaphragm 23 he will depress the treadle 43.

Downward movement of the treadle causes the valve stem 275 of the shoe clamping control valve 175 to be moved to cause oil to be admitted to the cylinder 127 between the pistons 129 and 131, and also causes the levers 431, 433 and 439, 441 to be swung anticlockwise together to move the stem 363 of the speed control valve into the position in which oil from the high capacity pump is fed into the supply line 305. The pistons 129 and 131 are thereby moved under the action of oil supplied from both pumps, to cause (a) firm clamping of the shoe bottom against the diaphragm portions of which will be so locally deflected, against the action of the spring pressed fingers 27 in the matrix box 25, that the diaphragm accommodates itself to the varying contours of the shoe bottom and seats itself snugly against the top of the insole lip and the material constituting the side wall of the cavity in the shoe bottom so as to seal the sides of the cavity, and (b) lifting of the cut-off valve 39 to open the duct 31 through the matrix device to the cavity in the shoe bottom. Forward movement of the valve stem 275 carries the member 465 well out of engagement with the pawls 459.

Downward movement of the treadle 43 also causes the bar 481 to rise thereby swinging the lever 491, 495 to move the reversing valve steam into the position in which the front end of the cylinder 181 communicates with the oil supply pipe line 305.

Forward movement of the valve stem 363 swings the lever 467, 469 clockwise (Fig. 11) to carry the roll 473 out of the depression 477 on the disc 475 to such an extent that, on rotation of the disc as the plunger starts to move forwards the roll is in engagement (or substantially so), with the concentric portion of the periphery of the disc. At this time therefore oil from both pumps is admitted to the cylinder 181 and the plunger 29 and pick up sleeve 31 are moved forwardly through the drum 11 at high speed. As the plunger advances the pick up sleeve 31 engages the rear end of the portion of the casting 35 in which the cylinder 33 is formed and its forward movement is arrested.

Further movement of the plunger takes place relatively to the sleeve and urges the filling material picked up by the sleeve into the cylinder 33 and, as the front end of the plunger 29 advances along the cylinder 33, filling material is urged therefrom, through the duct 31 in the matrix box, and into the shoe bottom cavity.

When the plunger 29 has moved forwardly some three quarters of its stroke the shaft 197 will have been turned anticlockwise from the position shown in Fig. 11 to such an extent that the rise 453 on the cam 449 urges the cam roll 447 rearwards to swing the lever 439, 441 clockwise (Fig. 11) to move the valve stem 363 further forwards (to a position in which the pawls 459 engage the depression 457 in the valve stem) to cut off supply of oil from the high capacity pump to the pipe

line 305, the roll 473 being swung away from the peripheral surface of the disc 475.

Forward movement of the plunger 29 continues, at low speed, actuated by the low capacity pump alone and this changeover to low speed is arranged to occur just before sufficient material has been extruded into the cavity to fill the cavity. This is arranged by the operator adjusting the stop formed by the arm 221 (by rotating the hand knob 231) forwardly or rearwardly in the machine to adjust the amount the sleeve overhangs the front end of the plunger at the conclusion of the rearward stroke thereof and thereby the amount of material which the sleeve will pick up on the next forward stroke of the plunger. The capacity of the pick up device will be so adjusted that the amount picked up by the device is a little more than is required to fill the cavity in each shoe of the particular run of shoes being operated upon.

The majority of the filling operation will thus be effected at high speed, only the end portion being carried out at low speed to enable the operator more readily to be able to determine the exact instant at which he must release the treadle to terminate the cavity filling operation. On release of the treadle the shoe clamping control valve stem moves rearwardly to cause the shoe to be unclamped and the cut off valve 39 to be lowered to close the duct 37 through the matrix device so as to prevent further material being extruded therethrough as the plunger completes its forward stroke, surplus filling material being returned to the drum via the passage.

Release of the treadle also causes the lever 431, 433 to swing clockwise (Fig. 11) to carry the lever 439, 441 rearwardly in the machine. The valve stem 363 of the speed control valve is however held in its forward position by the pawls 459 engaging the notch 457 in the stem until the shoe clamping control valve has moved rearwardly sufficiently for the member 465 to engage the tails of the pawls and swing the latter to cause them to release the valve stem 363 to the action of the spring 455 (Fig. 9). This arrangement ensures that the stem 363 cannot move rearwardly to its position (determined by engagement of the roll 473 with the concentric portion of the disc 475) in which oil from the high capacity pump is again admitted to the pipe line 305 to actuate the plunger at high speed until the cut-off valve is properly seated on its valve seat to close the duct through the matrix device. This ensures that bottom filling material is not squirted through the duct as the changeover to high speed occurs. On completion of the forward stroke of the plunger (at high speed) the stop screw 509 on the segment 503 engages the bar 481 and moves it rearwardly to release the block 493 from the depression 497 in the bar to allow clockwise swinging movement of the levers 491, 495 to occur with consequent movement of the reversing valve stem to its other position to change over the flow of oil from one end cylinder 181 to the other and so to reverse the direction of movement of the plunger.

The parts then return to their initial positions as hereinbefore described.

As the operator removes the shoe from the machine (as soon as the clamping means has released it) he may engage the shoe bottom with a heated smoothing roll 600 rotatably mounted on a spindle carried by a bracket 602 secured to the machine frame and move the shoe forwardly or rearwardly while pressing it against the roll to

cause the roll to smooth out the shoe bottom and iron out any slight unevenness in the bottom filling material therein.

With some mixtures of bottom filling material it may be found unnecessary to use the sleeve 39, sufficient material being worked into the cylinder 33 between successive operations of the machine due to the "milling" action of the agitating drum 11. In these circumstances it is desirable to provide a fine adjustment of the orientation of the cam 449 with respect to the shaft 197 so that the operator may readily and accurately determine the instant during the forward stroke of the plunger 29 at which the change over from high speed drive to low speed drive occurs. Such an adjustment will enable him so to set the cam 449 that the major portion of the cavity-filling operation takes place at high speed (to maintain a high rate of output from the machine) but the end portion of the operation takes place at low speed, thus giving the operator a better chance of determining the instant at which he should terminate the cavity filling operation.

The machine may therefore be modified by the provision of the adjusting means now to be described with reference to Figs. 14-16 of the accompanying drawings. In this modified form of the illustrative machine the cam 475 is moved to a position adjacent the right-hand bracket 199 (Fig. 12) and the lever 467, 469 is modified to bring the arm 469 into position to cooperate with the repositioned cam 475. Freely journaled on the shaft 197 at a location adjacent the left hand side of the cam 475 (as seen from the front of the machine) is a gear 601 (Fig. 16) having secured thereto a two-armed lever 603, 605 (Fig. 15). The cam 449 (Fig. 13) is replaced by a cam 607 (Fig. 15) having secured thereto a pair of ratchet segments 609, 611 (Fig. 16) the teeth on the two segments being oppositely disposed as is shown in Fig. 15. The cam is freely rotatable on a boss 613 on the shaft 197, a collar 615 secured to the shaft serving to retain the cam in position against movement endwise of the shaft.

The arm 603 of the lever 603, 605 carries a pin 617 extending transversely into a slightly oversize recess 619 in the cam 607. The cam 607 carries a transversely extending stud 621 on which pawls 623, 625 are pivoted, the pawls engaging the teeth of the ratchet segments 609, 611 respectively. The pawls 623, 625 are provided with extensions 627, 629 respectively, the extensions being connected by means of a spring 631 which urges the pawls into engagement with the teeth of the ratchet segments.

A pin 633 extending transversely from the arm 605 of the lever 603, 605 lies between the extensions 627, 629 of the pawls.

The gear 601 meshes with a gear segment 635 secured on a shaft 637 journaled in a bearing bushing 638 in a bracket 639 secured to the machine frame. The shaft 637 has secured to it a lever 641 to which is pivotally connected a rear end portion of a rod 643. A front end portion of the rod 643 is pivotally connected with a hand lever 645 which is pivotally mounted on a stud 647 carried by a bracket 649 bolted to the member 19. The hand lever 645 carries an index (not shown) cooperating with an arcuate scale 653 fixedly secured to the machine. Rearward movement of the hand lever by the operator results in clockwise swinging movement being imparted to the gear segment 635 and anticlockwise movement to the gear 601 and lever 603, 605. Such movement causes the pin 633 to engage the

tail 629 of the pawl 625 and thereby to swing the pawl out of engagement with the teeth of the ratchet segment 611. Continued movement of the arm 605 in the same direction then causes the pawl 623 to ratchet over the teeth of the segment 609 while movement of the arm 603 causes the cam 607 (through engagement of the pin 617 with the upper wall of the recess 619) to rotate in an anticlockwise direction relatively to the shaft 197. At the conclusion of anticlockwise movement of the arms 603, 605 the spring 631 acts to cause the pawl 625 to re-engage the teeth of the ratchet segment 611. When the pawls are each engaging the teeth of the respective ratchets the arm 605 is locked against movement relatively to the ratchet and hence the cam 607 is held against movement relatively to the shaft. As the shaft rotates during the operation of the machine the arms 603, 605, the cam 607 and the parts associated therewith all rotate with the shaft.

It will be readily understood that forward movement of the hand lever 645 will cause movement of the arms 603, 605 in a clockwise direction, freeing the pawl 623 from the teeth of the ratchet segment 609 and moving the cam 607 in a clockwise direction with respect to the shaft 197. By moving the cam in the appropriate direction relatively to the shaft prior to the commencement of an operation of the machine the operator may advance or retard the change over from high speed to low speed movement of the plunger 29 and so ensure that the change in speed occurs just prior to the completion of a filling operation on a shoe no matter what is the size 35 of the shoe being operated upon. Stop pins 655 extending transversely from the ratchet segment 611 limit, by engagement with the arm 605, the amount of relative movement that may be effected between the ratchet segments and the arm 40 and hence between the cam 607 and the shaft 197.

In the form of the machine shown in Figs. 14-21 a rotary type cut-off valve 661 (Figs. 17 and 18) for terminating flow of material through the duct in the matrix box, is used in place of the plunger type valve 39 shown in Figs. 3 and 4. Furthermore the cut-off valve is operated directly by actuation of a treadle arrangement and not by hydraulic means as above described with reference to the valve 39.

The valve has upper and lower cylindrical portions 663 and 665 respectively, the lower portion being of reduced diameter compared with the upper portion. The lower portion is provided with two diametrically opposed passageways 667 (see particularly Fig. 20) extending lengthwise of the valve, both of these passageways opening into a passage 669 (Figs. 17 and 18) cut obliquely through the upper portion of the valve. The lower portion of the valve is received in a cylindrical bushing 671 secured in the matrix box and replacing the bushing employed in the matrix box shown in Figs. 3 and 4.

The bushing 671 has an end plate like portions 673 (Fig. 20) provided with two ports 675 with which the passageways 667 in the valve may be brought into line by rotation of the valve and through which filling material may be extruded into a shoe bottom cavity. When the passageways 667 are aligned with the ports 675 the passage 669 is in communication with the cylinder 33. Rotation of the valve through 90° from this position shuts off the ports 675 and establishes communication between the cylinder 33 and the duct 45 through a passageway 677 in the valve.

The matrix 674 (Fig. 17) is recessed slightly to accommodate a flange or the rim of the portion 673. The ports 675 are therefore substantially in the plane of the matrix.

The valve is rotatably mounted in a bore in the casting 35, an upper part of the valve being received in a bushing 679 in the casting 35. Peripherally formed on the portion 663 of the valve is a series of gear teeth 681 arranged to mesh with the teeth of a segment 683 rotatably mounted on a bolt 685 carried by the casting 35. Formed integrally with the segment 683 is an arm 687 having a ball and socket connection with one end of a link 689. The other end of the link 689 has a ball and socket connection with one arm 691 of a bell crank lever pivoted on a bracket 693 secured to the left-hand one of the rods 121 (as seen from the front of the machine). The other arm 695 of the bell crank lever has pivoted thereon a trunnion block 697 through which extends an upper end portion of a valve-operating rod 699, washer 701 under nuts on the upper end of the rod being arranged to engage the upper and lower faces of the block. A lower end portion of this rod 699 is connected to treadle mechanism hereinafter described.

A spring 703 connected between a pin 705 in the segment and a pin 707 in the casting 35 tends to hold the segment 683 in either of its two extreme positions in which the valve is in its "cut-off" position or in its open position as far as the ports 675 are concerned the line of action of the spring crossing the axis of the stud 685 as the segment is moved from one position to the other.

The treadle arrangement in the form of the machine shown in Figs. 14-21 comprises the treadle 43 and its rearwardly extending arm 405 secured to the shaft 395 to which is also secured depending levers 401, 402 as hereinbefore described with reference to the form of machine shown in Figs. 1-13. The arm 405 is coupled to the shoe-clamping control valve as before while the levers 401, 402 are connected to other portions of the hydraulic circuit control gear as before and above described.

As is shown in Figs. 14 and 21 the shaft 395 has secured to it a forwardly extending arm 721 to which is pivotally connected, by means of a stud 723, a lower end of a rod 725 which extends upwardly through a yoke 727 and is threaded at its upper end to receive nuts 729. A compression spring 731 surrounds the rod 725 between the nuts 729 and the yoke 727. An upper end portion of the yoke is pivotally connected by means of a stud 733 to a disc 735 secured to a cross shaft 737 journaled in bearings in brackets 739 depending from the rod 113. Also secured to the cross shaft 737 is a lever 741 to which is pivotally connected a lower end portion of the valve operating rod 699.

Depression of the treadle 43 operates the shoe clamping control valve 175, swings the arm 721 downwardly to rotate the disc 735 and lever 741 (anticlockwise as seen in Fig. 21) to open the valve 661 (movement of the arm 721 being yieldably transmitted, through the spring 731, to the yoke 727) and also operates the speed control valve and reversing valve as hereinbefore described.

Rotation of the disc 735 in an anticlockwise direction on depression of the treadle 43 raises a second treadle 743 (Fig. 21) by means of a link 745 pivotally connected to the disc 735 and to the treadle 743. The treadle 743 is provided with a rearwardly extending arm 747 carrying a stop screw 749. The stop screw 749 is thus carried

out of engagement with a lug 751 projecting forwardly from a latch 753 pivoted on a pin 755 carried by a bracket 757 secured to one of the lower tie bars 9 (with capacity for heightwise adjustment relatively thereto). The latch 753 occupies the position shown in Fig. 21 prior to depression of the treadle 43, a rear face on the latch being engaged by a stop screw 749 in the bracket 757. When the treadle 43 is depressed and the stop screw 749 is moved out of engagement with the lug 751, a spring 761 urges the latch forwards so that a shoulder 763 on the latch rides beneath a catch plate 765 secured to the arm 405, forward movement of the latch being limited by engagement of a lug 767 on the latch with the rear end face of the catch plate.

The latch 753 thus serves to hold the treadle 43 in its depressed position and, at this time, there is a gap between the stop screw 749 and the lug 751.

When the operator observes that it is time to terminate a cavity filling operation he will depress the treadle 743. Such depression will rotate the disc 735 clockwise as seen in Fig. 21 moving the valve 661 to the "cut-off" position and thus terminating the filling operation. Such rotation of the disc 735 will raise the yoke 727 compressing the spring 731. As depression of the treadle 743 is nearing completion the stop screw 749 engages the lug 751 on the latch 753 and swings the latch clockwise to cause the latch to free the catch plate 765. The treadle spring 403 then restores the treadle 43 to its raised position, such action actuating the shoe clamping control valve to cause the shoe clamping means to free the shoe and actuating the speed control valve in the manner hereinbefore described with reference to the machine as shown in Figs. 1-13. This arrangement ensures that the valve is moved positively to its "cut-off" position before the shoe is released and before movement of the extruding plunger at high speed is reinitiated.

Having thus described our invention, what we claim as new and desire to secure by Letters Patent of the United States is:

1. A machine for filling a cavity in a shoe bottom including a matrix for closing said cavity, said matrix having a passage for the flow of filling composition to said cavity, means for forcing said composition through said passage, and a two-way valve arranged to control said passage with one port of said valve being adapted to open and close approximately in the plane of the matrix.

2. A machine for filling a cavity in a shoe bottom including a matrix for closing said cavity, said matrix being inclined downwardly and rearwardly and having a passage for the flow of filling composition to said cavity, means for guiding said composition through said passage, a two-port valve in said passage with one port arranged approximately in the plane of the matrix and the other port leading away from said matrix and adapted to open when the said one port is closed, and means for clamping a shoe with its bottom in firm engagement with the inclined matrix.

3. A machine for filling a cavity in a shoe bottom including a box with a matrix for closing said cavity, said box having a first passage leading from a source of filler composition to said cavity through the matrix and a second passage leading from the first passage, a two-way valve in the intersection of the two passages effective simultaneously to open the first passage and close the second or close the first and open the

second, and one port of said valve being arranged approximately in the plane of the matrix.

4. A machine for filling a cavity in a shoe bottom including a box with a matrix for closing said cavity, means for clamping a shoe bottom into firm engagement with said matrix, means for guiding a filler composition in a path leading through said matrix into said cavity and in a second path leading away from said matrix, and a rotary two-port valve for controlling said guiding means, said valve having one port in approximately the same plane as said matrix and the other port in control of the second path.

5. A machine for filling a cavity in a shoe bottom including a matrix for closing said cavity, a passage for guiding a filler composition through the matrix into the cavity, a cut-off valve controlling said passage, fluid pressure operated means for first moving said shoe bottom and matrix into engagement and subsequently extruding said composition through said passage, a first treadle operated mechanism for controlling said fluid pressure operated means, and a second treadle operated mechanism associated with the first treadle operated mechanism for operating said cut-off valve.

6. A machine for filling a cavity in a shoe bottom including a matrix for closing said cavity, said matrix having a passage for the flow of filler composition to said cavity, a valve arranged to control the passage, fluid pressure operated means for first moving said shoe bottom and matrix into engagement, said fluid pressure means including both relatively high and relatively low speed drives for forcing said composition through said passage, means for automatically shifting the effective drive from high speed to low speed before an extrusion cycle is completed, treadle mechanism for initiating said extrusion cycle, and a second treadle mechanism arranged to close said valve.

7. A machine for filling a cavity in a shoe bottom including a matrix box with a matrix inclined downwardly and rearwardly for closing said cavity, a container on said machine for a supply of filler composition, a first passage in said box leading from said container and through said matrix, a second passage leading from the first passage and back to the container, a two-way valve arranged to open either of said passages with one port of said valve being adapted to close approximately in the plane of the matrix, a fluid pressure operated system for forcing the said composition through said passages and extruding some of the composition into said cavity, said system comprising both relatively high and relatively low speed drives, means for automatically shifting the effective drive from high speed to low speed during an extrusion operation, and treadle mechanism coordinated with said two-way valve and said system for initiating and terminating said extrusion operation.
